DOUBLE IMAGE FACSIMILE PAGE PRINTER

Charles W. Burky, Park Ridge, and Erwin A. Gubisch, Chicago, Ill., assignors to Teletype Corporation, Chicago, Ill., a corporation of Delaware

Application April 14, 1941, Serial No. 388,430

14 Claims. (Cl. 178—11)

This invention relates to telegraph receiving apparatus and more particularly to facsimile printing telegraph receivers wherein messages are printed in page form.

It is an object of the present invention to provide a compact, simple and efficient telegraph receiving apparatus for facsimile printing in page form.

In accordance with one embodiment of the invention, apparatus is provided for drawing a sheet or web of paper from a supply thereof at a relatively slow rate of speed past a scanning drum of a width slightly greater than the width of the paper, said scanning drum being provided with a series of ribs spaced about its periphery for cooperation with styli being moved across the paper at right angles to the direction of the paper feeding motion. In the specific form of the invention disclosed herein the styli are curved and are mounted on a flexible metallic tape which is moved past the paper at a predetermined rate of speed relative to the rate of speed of paper being fed and the rotation of the scanning drum. Engaging the tape in the area thereof where it is held closely in association with, but out of contact with, the paper is a printing bar which will urge the tape toward the paper, a constantly fed ribbon of carbon paper being interposed between the moving tape and the paper web whereby when the printing hammer engages the tape to force it toward the paper, the carbon paper and the web of paper on which the characters are to be printed will be pinched or squeezed between the rotating scanning drum and the styli on the flexible metallic tape whereby characters will be inscribed on the paper, the carbon from the carbon tape being transferred to the paper at the points of contact between the stylus and the scanning ribs on the drum. The printing hammer is mounted for reciprocation by a pair of magnetic speaker motors, and it, together with the parts associated with it, constitute the only reciprocating assembly in the apparatus.

A better understanding of the invention may be had by reference to the following detailed description of the preferred embodiment thereof, when considered in conjunction with the accompanying drawings, wherein

Fig. 1 is a plan view of a facsimile page printer embodying the present invention;

Fig. 2 is a front elevational view of the apparatus shown in Fig. 1, parts being broken away more clearly to illustrate those parts positioned behind them;

Fig. 3 is a right end elevational view of the apparatus as shown in Fig. 1; and

Fig. 4 is a vertical sectional view taken along the line 4—4 in the direction of the arrows on Fig. 1.

In the drawings, where like reference characters designate the same parts throughout the several views, there is shown a main driving motor 10 mounted on a base 11. The motor 10 drives a main motor shaft 12 carrying a gear 13 which is meshed with and drives a gear 14 suitably fixed to a shaft 15 extending from the front to the rear of the machine and serving to transmit power to the various operating parts of the apparatus. It should be noted here that the usual covers provided for the apparatus have been omitted from the structure in all of the views so that the drawings will more clearly illustrate the operating parts of the apparatus.

The shaft 15 is journaled in suitable bearing brackets 16 and 17 which are fixed to main side plate 18 of a pair of main side plates 18 and 19. Fixed to the shaft 15 are a pair of gears 20 and 21, the gear 20 being intermediate the ends of the shaft 15 and the gear 21 being at the forward end of the shaft 15. The gear 20 meshes with a pair of gears designated 22 and 23. The gear 23 is secured to a shaft 24 on which there is mounted a scanning drum designated generally by the numeral 25.

The scanning drum 25 is formed with a plurality of ridges 33 on its outer periphery, the ridges extending parallel to the axis of the drum straight across the face thereof and being spaced apart a distance equal to the distance between like points on the characters being printed simultaneously on the paper, as will be described more in detail hereinafter. The drum extends substantially the entire distance between the side plates 18 and 19 and has cooperating therewith a paper feeding mechanism designated generally by the reference numeral 26 which serves to draw a web of paper 46 slowly, upwardly across the face of the drum.

The paper feeding mechanism 26 comprises a pair of serrated rollers 34 mounted upon a shaft 35 which has fixed to it a gear 36 meshing with a gear 37 on a stud shaft 38. The stud shaft 38 is journaled in a bracket 39 and carries at its lower end the gear 22 which meshes with gear 20 and is driven thereby. Cooperating with the feed rollers 34 are a pair of spring pressed pressure rollers 41. The rollers 41 are mounted on the free arms of bell crank levers 42 which are pivoted on the side plates 18 and 19 by means of

pivot pins 43 and are urged to rotate in a clockwise direction by contractile springs 44 connected to the other free arm of the bell crank 42 and to a projecting portion 48 of each of the side plates.

It is believed to be apparent from a description thus far that the scanning drum 25 is driven at a predetermined rate of speed and that the web of paper which has been designated 46 will be drawn past the scanning drum 25 at a rate of speed proportional to the speed of rotation of the drum 25 due to the fact that the roller 41 will press the web of paper 46 against the knurled feed rollers 34 thereby to draw the paper over the surface of the scanning drum 25 while the scanning drum is rotating. The paper 46 is drawn from a suitable supply thereof (not shown) over a guide roller 47, suitable means being provided for frictionally retarding the withdrawal of paper from the supply so that the paper will firmly engage the ridges 33 on the drum 25 and will be held relatively taut between the knurled feed roller 34 and the guide roller 47.

The forward extending ends of the side plates 18 and 19 are bent over as shown at 54 and 55, respectively (Fig. 1), to support a cross plate 56 which is secured to the bent over portions of 54 and 55 by any suitable means, for example, screws 57. Adjustably mounted on the plate 56 by means of threaded members 59 is a speaker motor supporting plate 60 which carries a pair of speaker motors designated generally by the numerals 61 and 62 and which also carries a bracket 64 on which there is adjustably mounted a roller 65 for applying tension to a scanning tape 66. The speaker motors 61 and 62 are identical in construction and only one, the motor 61, will be described in detail. This speaker motor 61, as shown most clearly in Figs. 1 and 4, includes a motor mounting plate 71 on which there is fixed an armature adjusting bracket 72, a coil 61, a laminated core 68, and core pole structure 69. The armature adjusting bracket 72 carries a rearwardly extending L-shaped member 74 and has in its forward portion an armature stop screw 73. The screw 73 and member 74 limit the movement of an armature 75 by forming abutments against which a screw 76 threadedly engaged in a horizontally extending portion 77 of the armature 75 will bump on movement of the armature. The armature 75 is hinged to an armature supporting plate 70 by means of a flexible metal reed 79 and the supporting plate 70 is mounted on a permanent magnet 78 fixed to the motor mounting plate 71. The screw 76 has a two-fold purpose, the head of it serving as stop surfaces which will strike against the adjusting screw 73 and the member 74 and also serving to hold a printing hammer or printing bar 81 on an L-shaped member 80 which is formed integrally with the armature 75. The printing bar 81 which is T shaped in cross section as seen in Fig. 4, extends across the length of the scanning drum 25 and serves to drive printing ridges 82 on the tape 66 into engagement with a carbon tape 83 guided between the web of paper 46 and the ridges 82 on the scanning tape 66. The scanning tape 66 is provided with three printing ridges 82 and is driven across the face of the scanning drum 25 at a speed proportional to the speed of the scanning drum and of course proportional, therefore, to the speed of travel of the web of paper 46 past the scanning drum. The surface of each ridge 82 at the sides immediately adjacent to the carbon tape 83 is of arcuate formation and has a curvature corre-

sponding to the curvature of scanning drum 25.

The scanning tape 66 is passed around two rollers 84 and 85 positioned at opposite sides of the apparatus. The roller 84 is freely rotatable on a stud shaft 86 fixed in a bracket 87 mounted on the side plate 19, whereas the roller 85 is fixed to a stud shaft 88 journaled in a bracket 89 and carrying at its upper end a gear 90 which meshes with the gear 21 described hereinbefore. The shaft 88 has secured to its lower end a gear 91 meshing with and driving a gear 92 which is mounted on a short shaft 93 and drives a gear 94 which in turn meshes with a gear 95 for driving a knurled tape feed roll 96 (Fig. 2) mounted on a shaft 97 common to the feed roll 96 and the gear 95. The carbon tape 83 is fed from a supply 99 at the rear of the machine over guide rollers 100 and 101 rotatably mounted in bracket 102 and 103, respectively, and will be drawn slowly across the web of paper 46 by the knurled roller 96 into engagement with which it is forced by a spring pressed roller 104 mounted on a bracket 105 which is pivoted on a rod 106 suitably mounted on a support member 107 secured to side plate 18 and urged into engagement with the knurled feed roll 96 by a contractile spring 108.

A more complete understanding of the apparatus described hereinbefore may be had from the following brief description of the mode of operation thereof. If it be assumed that a web of paper fed from a suitable supply has been directed over the guide roller 47 and drum 25 and between the knurled roller 34 and pressure roller 41, the apparatus will be in condition for operation. In order to initiate operation of the apparatus, a suitable switch may be closed to start the motor 10 in operation. This starting of the motor 10 may be accomplished in any suitable manner such as, for example, the manner shown in the copending patent application of R. E. Zenner, Serial No. 371,358, filed December 23, 1940, wherein there is shown a facsimile printer for printing on tape. After the motor 10 is started in this manner the motor will, through the shaft 12, drive the main shaft 15 thereby to transmit power to the various moving parts of the apparatus with the exception of the print hammer 81 which is driven by the speaker motors 61 and 62 connected to either wired or wireless telegraph receiving circuits. The knurled roller 34 will draw the web of paper 46 slowly past the scanning drum 25 which will be rotating at a rate of speed proportional to the speed at which the paper 46 is fed past it, and the scanning tape 66 will be driven past the web of paper also at a speed proportional to the speed at which the paper is fed. As the scanning drum 25 moves its ridges past the face of the web of paper 46, the paper will be pinched between the carbon tape 83 and the ridges 33 on the scanning drum at the points where the ridges on the scanning tape 66 engage the carbon paper, thereby to transfer carbon from the tape to the web of paper in lines of a length depending upon the length of time that the ridge on the scanning tape is in engagement with the carbon tape. The apparatus described will thus continuously receive signals in the form of magnet motor controlling impulses and will cause the armature of the magnet motor to oscillate in a manner similar to that described in the patents referred to hereinbefore.

It should be noted that the dimensions and speed of operation of the scanning drum 25, the paper feeding mechanism 26 and scanning tape

66 are so proportioned that two lines of identical printing will appear on the web of paper in the same manner as on the tape printed in an apparatus made in accordance with the showing in Kleinschmidt et al. Patent No. 2,131,741 patented October 4, 1938, and E. F. Kleinschmidt Patent No. 2,145,264 patented January 31, 1939. It should be noted also that the ridges 82 on the tape 66 are positioned equidistant one from the other and that there is always one of them positioned between the printing hammer 81 and the carbon tape 83. This results in the last character in each of the upper two identical lines of matter being duplicated as the first character in each of the two succeeding lines of identical characters. Also, due to the fact that the paper 46 travels continuously, the lines of printing will slope downwardly from left to right.

In the formation of the printed characters, the engagement of the paper 46 by the carbon tape 83 is controlled by the speaker motors 61 and 62 in response to polar signals received by them. For example, in forming the character E the motors will be energized to drive the hammer against the paper repeatedly for periods of relatively long or short duration, the period of longest duration being equivalent to the length of time it takes one of the ridges 33 on the scanning drum 25 to move a distance equal to the height of the character. In order to form the vertical line of the letter E the hammer will be operated once for the long period and will then be operated for relatively short periods to form the series of short lines which form the horizontal portions of the character, which are similar to those formed by the apparatus of the Kleinschmidt patents noted hereinbefore.

Although a specific apparatus has been described hereinbefore as illustrative of the invention, it should be understood that many modifications thereof could be made without departing from the scope of the appended claims.

What is claimed is:

1. A printing telegraph receiver comprising a printing hammer, means responsive to received signals for actuating said hammer, a ridged member movable in one direction past said hammer, a scanning member movable in a direction at an angle to the direction of movement of the ridged member, and means for moving a web of paper between the ridged member and the scanning member.

2. A facsimile printing apparatus comprising a rotatable scanning drum, means for drawing a web of paper across the drum, means movable across the moving web of paper, and means responsive to received signals for moving the means movable across the paper toward the scanning drum to mark the paper using the scanning drum as a platen.

3. A facsimile printing apparatus comprising a continuously driven ridged drum, a continuously driven ridged tape, a continuously driven paper feeding means for feeding a web of paper between the tape and drum, and signal responsive means for moving the ridged tape at right angles to its path of continuous movement to press the paper between the ridges on the drum and tape to mark it.

4. In a facsimile page printing apparatus, a rotating drum having ribs extending from its periphery and formed parallel to the axis thereof, a belt having ridges formed thereon movable past

the drum in timed relation to the rotation thereof, and a signal responsive means for moving the ridges on the belt toward the drum to pinch a page between the ribs and the ridges to effect printing.

5. In a facsimile page printing apparatus, a rotating drum having ribs extending from its periphery and formed parallel to the axis thereof, a belt having ridges formed thereon movable past the drum in timed relation to the rotation thereof, a signal responsive means for moving the ridges on the belt toward the drum to pinch a page between the ribs and the ridges to effect printing, and means for moving the page past the drum in timed relation to the rotation of the drum.

6. In a facsimile page printing apparatus, a rotating drum having ribs extending from its periphery and formed parallel to the axis thereof, a belt having ridges formed thereon movable past the drum in timed relation to the rotation thereof, a carbon tape positioned between the belt and the page, a signal responsive means for moving the ridges on the belt toward the drum to pinch a page between the ribs and the ridges to effect printing, and means for moving the page past the drum in timed relation to the rotation of the drum.

7. In a facsimile page printing apparatus, a rotating drum having ribs extending from its periphery and formed parallel to the axis thereof, a belt having ridges formed thereon movable past the drum in timed relation to the rotation thereof, a signal responsive means for moving the ridges on the belt toward the drum to pinch a page between the ribs and the ridges to effect printing, a carbon tape, and means for moving the tape continuously between the belt and the page.

8. In a facsimile page printing apparatus, a drum having straight line styli extending parallel to the axis thereof and positioned to extend radially outwardly from the surface thereof, a marking member movable in a plane parallel to the axis of said drum, means for moving a sheet of record material between the drum and marking member, and signal responsive means for moving the marking member towards the drum to effect marking on the record material.

9. In a facsimile page printing apparatus, a drum having straight line styli extending parallel to the axis thereof and positioned to extend radially outwardly from the surface thereof, a marking member movable in a plane parallel to the axis of said drum, means for moving a sheet of record material between the drum and marking member, carbon tape feeding means for feeding carbon tape between the marking member and the paper, and signal responsive means for moving the marking member toward the drum to pinch the carbon tape and record material between the marking member and styli to transfer carbon from the tape to the record material.

10. In a facsimile page printing apparatus, means for moving a sheet of record material in a predetermined path, a pair of cooperating marking means positioned for movement on opposite sides of the record material during its movement in said path, means for rotating one of said marking means, means for moving the other of said marking means in a path parallel to the axis of rotation of the rotatable marking means, and means for imparting relative movement to said marking means.

11. In a telegraph recorder, the combination of a rotating drum, a plurality of straight line recording styli on said drum, means for drawing a sheet of record material in a path tangential of the drum, means for drawing a marking tape in a path parallel to the axis of the drum, a plurality of traveling platen members movable in a path parallel to the axis of the drum, and signal responsive means movable to cause the platen members to engage the tape and compress the sheet and marking tape between a platen and the styli.

12. In a facsimile recorder the combination of a stylus member having a plurality of straight line stylus edges, means for manipulating the stylus member to move the stylus edges rapidly through a predetermined zone, a vibratory ridged means slowly movable across said zone, means for drawing a sheet of record material over said stylus member, means for moving a strip of pigment depositing material between the ridged means and the record material, and signal responsive means extending across the sheet of record material for actuating the ridged means to compress the strip and sheet between the stylus edges and the ridged means.

13. In a facsimile recorder, the combination of

means for drawing a record sheet through a predetermined path, means for drawing a carbon tape transversely of said path, a rotary stylus member having a plurality of stylus edges moving in the direction of movement of said sheet, a thin edged platen member movable transversely of said stylus edges opposite said sheet and carbon tape, and signal responsive means effective to press the platen and stylus members together to print on said sheet.

14. In a facsimile recorder, the combination of means for drawing a record sheet through a predetermined path, means for drawing a carbon tape transversely of said path, a rotary stylus member having a plurality of stylus edges moving in the direction of movement of said sheet, a thin edged platen member movable transversely of said stylus edges opposite said sheet and carbon tape, a printing hammer member associated with the platen member extending transversely of the path of movement of the sheet, and signal responsive means effective to operate said hammer member to press the platen member toward the stylus edges.

CHARLES W. BURCKY.
